UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE SIGNALING SYSTEM.

1,232,944.

Specification of Letters Patent.

Patented July 10, 1917.

Continuation of application Serial No. 101,766, filed June 5, 1916. This application filed September 22, 1916.
Serial No. 121,565.

To all whom it may concern:

- Be it known that I, ALBEN E. LUNDELL, a citizen of the United States, residing at New York, in the county of Bronx and State of New York, have invented certain new and useful Improvements in Telephone Signaling Systems, of which the following is a full, clear, concise, and exact description.
- 10 This invention relates to signaling systems.
- The present is a continuation of my application, Serial No. 101,766, filed June 5, 1916.
- 15 The principal object of this invention is to provide means, which may be in part common to all of the connecting circuits of a position and in part individual to the various circuits, for enabling the operator to 20 predetermine and control the character of ringing current that is automatically applied in establishing connection with a line, to ring a particular station of that line, and to ascertain the sort of ringing current a 25 particular connecting circuit is set to apply.
- The system of this invention is such that the setting of the operator's switching apparatus to predetermine the character of ringing current that is to be applied automatically by a particular connecting circuit, brings about certain changes in said circuit which not only are instrumental in controlling the character of the signaling current that this circuit is thus adapted to 30 apply, but also control the display of a corresponding one of a number of signals associated with the operator's switching apparatus to indicate to the operator the sort of ringing current for which the connecting 35 circuit is set. The organization of the system is such that when a connecting circuit is changed through the agency of the operator's switching mechanism to adapt it for the application of a certain sort of ringing 40 current, it remains set to apply this sort of current until the connection is taken down or until the operator manipulates her switching mechanism.
- The selective application of ringing current to the connecting circuit is preferably 45
- effectuated through the agency of an automatic switch of the "sequence switch" type, this switch being arranged to establish the different ringing current combinations in different positions of its movement and being arranged to move to any predetermined one of its ringing positions under the control of the individual connecting circuit controlling mechanism set by the switching apparatus common to the position.
- 50 In multi-office telephone exchange systems in which party lines are used, the selection of the proper signaling current is usually controlled by an operator located at the office in which the desired party line terminates. Thus, the operator, in addition to the setting up of the connection, is burdened also with the selection of the proper signaling means. The selection of the signaling means being usually controlled by a variably 55 operable switching device, it may happen that while this device is moving to a desired operating position through intermediate operating positions, a signaling current source is connected to the line and the stations or station responsive to such current source are signaled.
- 60 It is the further object of this invention to overcome these difficulties by providing an improved multi-office party line telephone system in which the selection of the proper signaling means is controlled from a distant point, i. e., outside of the office in which the party line terminates the signaling of not wanted stations being positively 65 prevented.
- 65 According to one feature of this invention, means are provided at one office for controlling the selective operation of variably operable switching devices located at 70 a second office and adapted to select the proper signaling means for party line stations.
- 75 According to another feature of this invention, means are provided, in association with the variably operable switching devices, for positively preventing the connection of signaling current sources until the switching device has reached the desired position.

Still another feature of this invention has for its purpose the selection of the desired signaling current by means of a device adapted to convey to an operator the called subscriber's designation, whereby the sending of impulses in addition to those designating the number of the line, is obviated.

According to another feature of this invention, the selection of the proper signaling means follows immediately upon the extension of the calling line to the called office.

The drawings represent a semi-automatic telephone exchange system embodying the present invention. In Figure 1 a calling line circuit, a connecting operator's cord circuit and a selector switch adapted to extend the same are shown; Fig. 2 represents a B operator's position and associated apparatus and a party line circuit; Figs. 3 and 4 represent the called number indicating apparatus at the B operator's position, and the distributing switch by means of which this apparatus may be associated with the selected trunk; and Fig. 5 represents the connecting operator's controlling device by means of which the selector switch and the other selectively operable switching devices may be adjusted. The drawings should be arranged by placing Fig. 5 below Fig. 1, Fig. 2 to the right of Fig. 1, Fig. 3 to the right of Fig. 2 and Fig. 4 to the right of Fig. 3. Only so much is shown of the circuits and controlling apparatus as is necessary for a clear understanding of the present invention. The selector and sequence switches and the controlling apparatus for such switches are only schematically indicated, as their detailed arrangement has no bearing on the present invention. Devices of this type are well-known in the art and a description of the same may be found in Patent No. 1,168,319 of January 18, 1916.

A clear understanding of the invention may be had from the following detailed description and the appended claims.

A calling subscriber at substation 100 desiring to obtain a connection with one of the parties of a line No. 731 (Fig. 2), 50 moves his receiver from the switchhook, whereupon relay LR becomes energized and lights lamp CL. A connecting operator noticing lamp CL lighted, inserts plug 101 into an answering jack 102 in which the calling subscriber's line terminates. A circuit is established thereupon from grounded battery, through the winding of a cut-off relay CO, the sleeve contacts of jack 102 and plug 101, and the winding of relay 103, 55 to ground. Relay CO opens the circuit of relay LR, which in turn extinguishes lamp CL. Relay 103 closes a circuit from ground through its armature and front contact, a contact 104 and the power magnet of a sequence switch 105, to grounded battery,

and this sequence switch moves under the control of its normal spring 106 into position 2.

When sequence switch 105 reaches position 2, a circuit is closed from ground through a sequence switch contact 107, conductor 108, a contact 500 and the power magnet of a sequence switch 501 to grounded battery for moving this sequence switch into position 2. A circuit is now closed from grounded battery, through the winding of a magnet 502, a sequence switch contact 503 and the left-hand back contact and armature of a relay 504 to ground. Under the control of magnet 502, wipers 505 to 509 of a cord finder switch are moved over a contact bank in an upward direction. When the wipers reach contacts 510 to 514, individual to a cord or trunk 109, which was taken in use by the operator in extending the call, a circuit is closed from ground through a sequence switch contact 110, conductor 111, contact 511, wiper 506, a contact 515 of sequence switch 501 and the winding of relay 504 to grounded battery. Relay 504 opens at its left-hand back contact the circuit of magnet 502, whereupon the finder is arrested with its wipers on the contacts representing trunk 109. Relay 504 closes a circuit from ground, through its left-hand armature and front contact, a contact 516 and the power magnet of sequence switch 501 to grounded battery for driving this switch out of position 2 into position 3. When the sequence switch 501 moves out of position 2 and opens contact 515, relay 504 does not become deenergized, a locking circuit being closed from grounded battery, through the winding of this relay, sequence switch contact 517, the right-hand front contact and armature of relay 504, wiper 507, contact 512, conductor 112 and sequence switch contact 113 to ground.

The connecting operator depresses now a listening key 114, connecting thus her telephone set 115 through the trunk 109, in telephonic association with the calling substation 100.

In accordance with the instructions received from the calling subscriber, the operator sets up on her keyboard (Fig. 5) the number of the called subscriber. Supposing that the called subscriber's number is 731-W, and that the called line terminates in an office to which lead a plurality of trunk lines terminating in the tenth group of contacts of a district selector 116, the operator depresses key 518 in the district, key 519 in the hundreds, key 520 in the tens, key 521 in the units and key 522 in the stations row of keys. These keys control a double series of counting relays (zero to nine) operable in sequence by the action of a stepping relay 523. It is noted that

the hundreds, tens and units keys are wired in the same manner as shown in connection with the station and district rows of keys. The operator then depresses a start key 524, closing a circuit from ground, through the contact of this key, a contact 525 and the power magnet of sequence switch 501, whereupon this sequence switch moves out of position 3 into position 4.

10 When sequence switch 501 reaches position 4, a circuit is closed from grounded battery, through the power magnet of an allotter sequence switch 526, contact 527 of sequence switch 501, and contact 528 of the allotter (which is supposed to be in position 1) to ground. Under the control of this circuit, the allotter sequence switch is moved out of position 1 into position 6. In this position of the allotter, another finder 20 such as 529 is set in readiness for operation, due to the closure of a circuit from ground, through contact 530, a contact 531 and the power magnet of sequence switch 501 associated with the finder 529 to grounded battery. This sequence switch was standing in position 18 and will now be moved into position 1.

Sequence switch 105 being in position 2, a fundamental circuit is established from 30 grounded battery, through the winding of a relay 117, a sequence switch contact 118, a conductor 119, contact 513, wiper 508, a sequence switch contact 533, a conductor 534, the outer armature and back contact of 35 the upper zero counting relay, conductor 535, the winding of the stepping relay 523, wiper 509, contact 514, a conductor 120, and a sequence switch contact 121 to ground. Relay 117 becomes energized and closes a 40 circuit from ground, through its right-hand armature and front contact, a sequence switch contact 122, a conductor 123, and the power magnet of sequence switch 105 to grounded battery, for driving this sequence switch into position 3, in which position relay 117 remains energized, due to the closure of a locking circuit through its left-hand front contact and armature, and a sequence switch contact 124.

50 Stepping relay 523 also becomes energized and closes a circuit from ground, through its front contact and armature, a sequence switch contact 536, a conductor 537, the contact of key 518, conductor 538, the armature and back contact of the upper counting relay 9 and the winding of the lower counting relay 9 to grounded battery. The lower counting relay 9 becomes energized and closes a circuit from ground, 60 through a sequence switch contact 539, conductor 540, the armature and front contact of the lower counting relay 9, the windings of the upper and lower counting relays 9 to grounded battery. The upper counting relay 9, however, is short-circuited, due to

the closure of a shunt from its winding through conductor 538, key 518, conductor 537, sequence switch contact 436, and the front contact of the stepping relay 523 to ground.

In position 3 of the sequence switch 105, a circuit is closed from grounded battery, through the winding of a driving magnet 125, sequence switch contact 426, and the right-hand front contact and armature of relay 117 to ground. The magnet 125 by attracting its armature 127, forces a brush rod 128 against a roller 129, constantly rotating in the direction indicated by the arrow. Under the control of this roller, 75 the brush rod 128, with wipers 130, 131 and 132, and a commutator brush 133 mounted thereon is moved in an upward direction. Wipers 130, 131 and 132 are adapted to wipe over the contacts of terminal bank 80 134, and brush 133 is adapted to travel over the conducting and insulating segments 135 and 136 of a commutator plate 137.

When brush 133 reaches the first conducting plate 135 it connects ground 90 through a conductor 138, sequence switch contacts 139 and 124 to relay 117, causing thus the short-circuiting of stepping relay 523. Upon its deenergization, relay 523 removes the short circuit from around the 95 winding of upper counting relay 9, and this relay becomes energized. The upper counting relay 9 connects conductor 538 through its armature and front contact and the armature and back contact of the upper counting relay 8 to the lower counting relay 8, which then operates in the same manner as the lower counting relay 9, to close a circuit for the upper counting relay 8, when brush 133 reaches the first insulated 100 segment 136, whereupon the short circuit is removed from the winding of the stepping relay 523, and this relay permits the operation of the lower counting relay 8. The operation of the counting relays continues in the same manner as described in connection with counting relays 9 and 8, until the upper zero counting relay becomes energized. This relay opens at its outer 105 armature and front contact, the fundamental circuit, preventing thus the reenergization of stepping relay 523. The circuit of relay 117 is opened when brush 133 encounters the next insulating segment.

Relay 117 closes a circuit from ground, 110 through its right-hand armature and back contact, a sequence switch contact 140, conductor 123, and the power magnet of sequence switch 105 to grounded battery for moving this sequence switch into position 6. 115 A circuit is now closed from grounded battery through the winding of a test relay 140' and a sequence switch contact 141 to ground. The test relay becomes energized and assuming that the first trunk in the tenth group is 120 130 135

busy and a ground is connected to test terminal 142 of such trunk, relay 140' remains locked up due to the extension of this ground through test wiper 132, a conductor 143, and the right-hand armature, front contact and the winding of relay 140' to grounded battery. The sequence switch 105 is now in position 7, it being driven there by a circuit closed through the left-hand 70 armature and front contact of relay 140' and a sequence switch contact 144. Relay 140' closes a circuit from ground, through its left-hand armature and front contact, a sequence switch contact 145, and the winding 75 of the driving magnet 125 to grounded battery, and this magnet will cause the further travel of the wipers.

When the wiper 132 engages test terminal 146, connected in multiple with the test 80 terminals of trunk 147, 148 in all other district selectors, and does not find a ground connected to this terminal, relay 140' becomes deenergized, and opens at its left-hand armature and front contact, the circuit 85 of magnet 125, causing thus the stopping of selector switch 116. By releasing its right-hand armature relay 140' connects a ground potential through a sequence switch contact 149, its right-hand back contact 90 and armature, conductor 143, wiper 132, terminal 146, and conductor 150 to the multiples of terminal 146. The seizure of trunk 147, 148 by other district selectors is thus prevented. A circuit is also closed 95 from ground through the left-hand armature and back contact of relay 140', a contact 151, and the power magnet of sequence switch 105 to grounded battery, for driving the sequence switch out of position 7 into 100 position 11.

Upon the energization of the upper zero counting relay, a circuit is closed from ground, through a sequence switch contact 541, the inner armature and front contact 110 of the upper zero counting relay, and the power magnet of sequence switch 501 to grounded battery, for moving the sequence switch into position 6. When the sequence 115 switch 501 leaves position 4, a locking circuit of the counting relays is opened at sequence switch contact 539, and these relays become deenergized.

When sequence switch 501 reaches position 6, a new fundamental circuit is established from ground (Fig. 2), through a sequence switch contact 200, trunk conductor 148, wiper 131, a sequence switch contact 152, conductor 120, contact 514, wiper 509, the windings of stepping relay 523, conductor 535, the outer contact and armature of the upper zero counting relay, conductor 534, sequence switch contact 533, wiper 508, contact 513, conductor 119, a sequence switch contact 153, wiper 130, conductor 147, a sequence switch contact 201, and the winding 120 of a relay 202 to grounded battery. Relay 202 closes a circuit from ground through its right-hand armature and front contact, a sequence switch control 203, conductor 204, and the power magnet of sequence switch 125 to grounded battery, for driving this sequence switch out of position 1 into position 2. A circuit is now closed from ground, through sequence switch contact 206, conductor 207, a contact 300 and the power magnet of a sequence switch 301 to grounded battery, for moving this sequence switch out of position 1 into position 2.

A circuit is established from grounded battery, through the right-hand armature 80 and back contact of a relay 302, a sequence switch contact 303 and the winding of a magnet 304 to grounded battery. Under the control of magnet 304, wipers 305, 306, 307, 308, 309 and 310 of a trunk finder switch are moved in an upward direction over a terminal bank containing contacts representing trunks. When these wipers reach a set of contacts 311, 312, 313, 314, 315 and 316 individual to trunk 147, 148 seized 90 by district selector 116, a circuit is established from ground through a sequence switch contact 208, conductor 209, contact 311, wiper 305, a sequence switch contact 317, and the winding of relay 302 to grounded 95 battery. Upon energization relay 302 opens at its right-hand back contact the circuit of magnet 314, causing thus the arresting of the trunk finder switch. This relay closes a circuit from ground through its right-hand armature and front contact, a contact 318 and the power magnet of sequence switch 301 to grounded battery, for driving this sequence switch out of position 2 into position 6. Relay 302 is maintained 100 energized due to the closure of a locking circuit from grounded battery through its winding, a sequence switch contact 319, the left-hand front contact and armature of relay 302, wiper 306, contact 312, conductor 320, and a sequence switch contact 208' to ground.

A circuit is now closed from ground, through a sequence switch contact 321, wiper 308, contact 314, a conductor 322, a contact 115 120 209, and the power magnet of sequence switch 205 to grounded battery, for driving this sequence switch into position 3. A circuit is closed from ground, through the right-hand armature and front contact of relay 202, a sequence switch contact 210, a conductor 211, contact 316, wiper 310, a sequence switch contact 323, a conductor 324, and the winding of a stepping magnet 400 to grounded battery. Magnet 400 is adapted 125 to move by means of a ratchet and pawl arrangement, an arm 401, by one step upon each deenergization.

Upon the energization of the stepping relay 523, a circuit is established from ground, 130

through the front contact and armature of this relay, a sequence switch contact 542, a conductor 543, the hundreds key 519, a conductor 544, the armature and back contact of the upper counting relay 7, and the winding of the lower counting relay 7 to grounded battery. In the same manner as above described, the lower counting relay 7 becomes energized and prepares a circuit for the upper counting relay 7.

Upon energization, magnet 400 closes a circuit from ground, through its armature and front contact, arm 401, conductor 402, and the power magnet of a hundreds number indicator 403, to grounded battery. The number indicators 403, 404, 405 and 406 are of the well-known sequence switch type, and control the contacts shown in Fig. 4 between the dotted lines to the right and left of the indicators, respectively. While these indicators are moving between the positions indicated at their respective normal springs 407, 408, 409, 410, they close contacts 411, 412, 413 and 414, respectively. Thus a ground will be intermittently connected through contact 411, conductor 419, a sequence switch contact 325, wiper 309, contact 315, conductor 326, a sequence switch contact 212, and the left-hand armature and front contact of relay 202 to the fundamental circuit in the same manner as through commutator brush 133. The stepping magnet 523 is shunted as many times as contact 411 is closed for controlling the successive 30 operation of the counting relays.

When the upper zero counting relay is energized, the indicator 403 is in position 7. The opening of the fundamental circuit by the upper zero counting relay results in the deenergization of relays 523 and 202, and the movement of sequence switch 501 into position 8. Relay 202 opens at its right-hand armature and front contact the circuit of stepping magnet 400, whereupon this magnet becomes deenergized and moves arm 401 into position 2, in which position indicator 404 is connected in circuit. Indicator 404 operates in the same manner as indicator 403, with the difference that it will be stepped into a position determined by key 520. After the stepping of indicator 404, sequence switch 501 is moved into position 10, and magnet 400 moves the arm 401 into its third position, connecting indicator 405 into circuit, and after this indicator has been stepped in accordance with the predetermined number of counting relays connected in circuit under the control of the units key 521, sequence switch 501 moves into position 12, and arm 401 into position 4, whereupon indicator 406 is operative.

After the impulses predetermined by key 522 have been received under the control of contact 414, sequence switch 501 moves into position 16, and the fundamental circuit is

opened at the back contact of the upper zero counting relay. The pawl and ratchet arrangement of magnet 400 is so constructed that upon the fourth deenergization of this magnet, the arm 401 is returned to its normal position. In position 16 of the sequence switch 501, a circuit is closed from ground, through a sequence switch contact 545, wiper 505, contact 510, conductor 546, and a contact 154 and the power magnet of sequence switch 103 to grounded battery, for moving this sequence switch out of position 11 into position 16. When contact 113 is opened, relay 504 becomes deenergized, and closes a circuit from ground, through its left-hand armature and back contact, a contact 547, and the power magnet of sequence switch 501 to grounded battery, for moving the sequence switch into position 17. A circuit is then closed from ground, through a sequence switch contact 548, and the winding of a magnet 549 to grounded battery. Under the control of magnet 549, the wipers 505 to 509 of the cord finder switch are driven in a downward direction, and when they reach the normal position, contact 550 of the finder switch is closed and a circuit is established from ground through contact 550, a contact 551 and the power magnet of sequence switch 501 to grounded battery, for moving this sequence switch into position 18. The sequence switch will remain in this position until allotter 526 is moved into position 1, and closes a circuit through its contact 528 and a sequence switch contact 552, for driving the sequence switch out of position 18 into position 1, and allotting thus the cord finder for service.

As soon as the indicator switch 406 moves out of position N, a contact 420 is closed, and upon the last deenergization of magnet 400 a circuit is established from ground, through the armature and back contact of this magnet, contact 420, conductor 421, a contact 328 and the power magnet of sequence switch 301 to grounded battery, for moving this sequence switch out of position 3 into position 7. A circuit is then closed from ground through sequence switch contact 329, wiper 307, contact 313, conductor 330, a contact 213 and the power magnet of sequence switch 205 to grounded battery, for moving this sequence switch out of position 3 into position 7. When sequence switch 205 moves out of position 3, relay 202 becomes deenergized. When sequence switch 205 reaches position 4, a circuit is closed from grounded battery, through the winding of a relay 214, the primary winding of a repeating coil 215, a sequence switch contact 216, trunk conductor 147, wiper 130, a sequence switch contact 149, the contact of a re-ringing key 161 and the secondary winding of a repeating coil 162 to ground. Relay 214 becomes energized, and connects 130

grounded battery through a resistance 217, its right-hand armature and contact 218 and the winding of a relay 219 to ground for energizing relay 219.

- 5 While sequence switch 205 is traveling from position 4 to 5, a relay 220 is energized by a circuit extending from grounded battery, through a sequence switch contact 221 and the left-hand winding of this relay 10 to ground. When sequence switch 205 leaves position 5, a holding circuit is established for relay 220 from ground, through the right-hand winding, armature and front contact of this relay and sequence switch 15 contacts 222 and 223 to grounded battery.

In position 7 of sequence switch 301, a circuit is closed from ground, through a sequence switch contact 334, a conductor 335 and lamps 415, 416, 417 and 418 in multiple to grounded battery. When sequence switch 205 reaches position 7, a circuit is closed from ground through a sequence switch contact 229 and a lamp 230 to grounded battery. The lighting of lamp 230 indicates to the B operator that she may complete the connection and lamps 415 to 418 indicate that line No. 731, party W, is wanted. The operator inserts a plug 224 into a jack 225, in which the line No. 731 terminates. A circuit is established from grounded battery, through the winding of relay 226, the sleeve contacts of plug 224 and jack 225 and a resistance 227 to ground.

Relay 226 closes a circuit from ground, 35 through its armature and front contact, the left-hand armature and front contact of relay 220, a contact 228 and the power magnet of sequence switch 205 to grounded battery, whereupon this sequence switch is 40 moved out of position 7 into position 9. When moving out of position 7, contact 208' is opened, whereupon relay 302 becomes deenergized and closes a circuit from ground, through its right-hand armature 45 and back contact, a contact 336 and the power magnet of sequence switch 301 to grounded battery, for moving this sequence switch into position 10. Upon the opening of contact 334 the lamps 415 to 418 are 50 extinguished. In position 10 of the sequence switch 301, a circuit is closed from ground, through sequence switch contact 337, conductor 338, a contact 440, and the power magnet of indicator switch 403 to 55 grounded battery for moving this switch out of position 7 into its normal position. In the same manner a ground is connected through the contacts of sequence switch spring 339, conductors 340, 341 and 342 and 60 indicator contacts 441, 442 and 443 to the power magnets of indicator switches 404, 405 and 406, respectively, for moving these switches into their normal position.

In position 10 of sequence switch 301, a 65 circuit is established from ground, through

sequence switch contact 343 and the winding of a magnet 344 to grounded battery and under the control of this magnet the brushes 305 to 310 of the trunk finder switch are driven in a downward direction. When they reach their normal position, a contact 345 is closed and a circuit established from ground, through contact 345, a contact 346 and the power magnet of sequence switch 301 to grounded battery. The sequence 70 switch moves into position 17. When all the indicator sequence switches reach their normal position, a circuit is closed from ground, through contacts 444, 445, 446 and 447, a conductor 448, a contact 347 and the 75 power magnet of sequence switch 301 to grounded battery for driving this sequence switch into position 18.

While the sequence switch 301 is moving between positions 6 and 17, if an allotter 80 sequence switch 348 reaches position 1, a circuit is closed from ground, through allotter contact 349, sequence switch contact 350 and the power magnet of allotter 348 to grounded battery for moving this allotter 85 into position 4. In this position of the allotter, ground is applied through an allotter contact 351 and a contact 352 of a sequence switch associated with another trunk finder switch, for moving that sequence switch out 90 of position 18 into position 1 and allotting thus that trunk finder for service. As soon as the allotter reaches again position 1, a circuit is closed through contact 349 and sequence switch contact 353 for moving sequence switch 301 out of position 18 into 95 position 1, whereupon the trunk finder will be set in readiness for service.

When sequence switch 205 leaves position 8, the holding circuit of relay 220 is interrupted at contact 223, and this relay releases 100 its armatures.

Cams 231, 232 and 233 are mounted on a constantly rotating shaft 234. These cams are arranged in such a manner that 231 and 110 232 actuate their respective contact springs 235 and 236 simultaneously, whereas cam 233 actuates its contact spring 237 prior to the actuation of contacts 235 and 236. When cam 233 actuates spring 237, a circuit is 115 established from ground, through the armature and front contact of relay 226, a sequence switch contact 238, contact 237 and the power magnet of sequence switch 205 to grounded battery, and this sequence 120 switch is moved out of position 9 into position 10. In position 10 of the sequence switch, a circuit is closed from grounded battery, through the left-hand armature and front contact of relay 214, a conductor 239, the windings of relays 240 and 241, a sequence switch contact 242, the left-hand back contact and armature of relay 220 and the front contact and armature of relay 226 to ground. Relay 240 becomes energized. 125 130

Relay 241 cannot become energized, due to a shunt placed around its winding through the armature and back contact of a ringing cut-off relay 250. Upon the subsequent actuation of contact 235 by cam 231, a circuit is established from a positive superimposed signaling current source 251, contact spring 235, the left-hand winding of ringing cut-off relay 250, sequence switch contact 252, conductor 253, the upper front contact and armature of ringing relay 240, the tip contacts of plug 224 and jack 225, limb 254 of the called line, the relays 255 at the stations J, R, M, W, in multiple, limb 256 of the called line, the ring contacts of jack 225 and plug 224, the lower armature and front contact of relay 240, conductor 257, and a sequence switch contact 258 to ground.

The relays 255 are responsive to superimposed signaling currents sent out from sources 251 and 259, and by attracting their armatures connect the bells of all stations into the ringing circuit, but only the bell associated with station W will respond to the current flowing through the circuit. The ringing cut-off relay 250 is marginal, and will not become energized until the called party removes his receiver from the switchhook. When this happens relay 250 becomes energized, current being supplied thereto from sources 251 or 260, depending upon whether contact 235 is actuated or not at this time. Upon the energization of ringing cut-off relay 250, the shunt is removed from around the winding of relay 241, and this relay, by attracting its armature, short-circuits relay 240. A supervisory relay 261 is energized then in the well-known manner, and causes in turn the energization of a supervisory relay 163 at the connecting operator's position.

When the called party desires disconnection he restores his receiver to the switchhook. Supervisory relay 261 becomes de-energized, deenergizing in turn supervisory relay 163, and if supervisory relay 164 has also been deenergized in response to the hanging up of the receiver at the station 100, the connecting operator removes plug 101 from jack 102. Relay 103 becomes deenergized and closes a driving circuit through sequence switch contact 165 for moving sequence switch 105 out of position 16 into position 18. A circuit is now closed through sequence switch contact 166 for energizing a magnet 167 and under the joint control of this magnet and a constantly rotating roller 168, the brush rod 128 of selector 116 is restored to normal. A circuit is then closed from ground, through brush 133, a normal conducting segment 169, conductor 170, a contact 171 and the power magnet of sequence switch 105 to grounded battery. Sequence

switch 105 moves into position 1 and magnet 167 becomes deenergized.

Selector 116 being restored, relay 214 becomes deenergized and opens the circuit of relay 219. A circuit is then closed from ground, through the back contact and armature of relay 219, a conductor 245, a contact 246 and the power magnet of sequence switch 205 to grounded battery, for moving this sequence switch out of position 10 into position 1. When this sequence switch reaches position 1, the lamp 230 is again lighted by way of sequence switch contact 229 and the front contact and armature of relay 226. The B operator noticing the signal removes plug 224 from jack 225, whereupon the apparatus is restored to normal.

If the called party hangs up his receiver before the calling party has finished the conversation, the calling party will instruct the connecting operator to rering the called party. The connecting operator actuates key 161 and opens thus the circuit of relay 214. Upon the deenergization of this relay, relay 219 is maintained energized by a circuit extending from ground, through the winding of relay 219, contact 243, conductor 244, the primary of repeating coil 215, sequence switch contact 247, conductor 148, wiper 131, the winding of relay 163 and the secondary of repeating coil 162, to grounded battery. The deenergization of relay 214 causes the unlocking of relay 241, and when relay 214 again becomes energized upon the releasing of key 161, it will establish in the same manner as above described an actuating circuit for relay 240, and this relay will cause the application of ringing current to the called line in the above described manner.

The bells at the party line stations are arranged in such a manner that the bell of station W responds if the positive current source 251 is connected to the tip side 254 and ground to the ring side 256 of the line. The bell of party M acts if the negative current source 259 is connected to the tip side 254 and ground to the ring side 256 of the line. The bell of party R operates if positive current source 251 is connected to the ring side 256 and ground to the tip side 254 of the line. The bell of party J responds when the negative current source 259 is connected to the ring side 256 and ground to the tip side 254 of the line.

When the operator inserts plug 224 into jack 225 for ringing party W, first the sleeve contacts of the plug and jack may contact, resulting in the energization of relay 226, whereupon, as above described, sequence switch 205 moves into position 9. While the plug is being pushed into the jack, the tip of plug 224 may contact with the ring of the jack. Should the ringing current source

251 already be connected through contact 252, positive pulsating current would be applied to the ring conductor 256 and thus a station like R, where the bell is normally connected to the ring side of the line, would be signaled. However, as above described, contact 252 is closed only after cam 233 has operated spring 237, that is to say, while both ringing current sources 251 and 259 are disconnected at contact springs 235 and 236 of cams 231 and 232. Due to this arrangement, the touching of the ring contact of jack 225 by the tip of plug 224 will not result in the ringing of a station, this being performed only after the plug has been positively inserted into the jack.

If the signaling of party R is desired, the connecting operator's controlling apparatus controls the moving of indicator 406 into position R, in which position contacts 425 and 426 are closed. When, therefore, sequence switch 205 reaches position 8, a circuit is established from grounded battery through contact 426, conductor 427, sequence switch contacts 260 and 222, and the right-hand front contact, armature and winding of relay 220 to ground. The relay 220 will thus not be deenergized when contact 221 is opened, but remains held up through this circuit until the sequence switch reaches position 11, whereupon a new circuit is closed for relay 220 from grounded battery through contact 425, conductor 428, sequence switch contacts 261 and 222 and the right-hand contact, armature and winding of relay 220 to ground, for maintaining this relay energized. Relay 220 keeps thus the driving circuit of sequence switch 205 closed at its left-hand armature through sequence switch contact 228 until the sequence switch reaches position 14, whereupon the holding circuit of relay 220 is opened at contact 261 and the sequence switch 205 is moved under the control of its normal spring into position 15. The circuit of relay 240 being held open at the left-hand back contact of relay 220, this relay 240 cannot become energized until sequence switch 205 leaves position 14. When cam 231 actuates contact spring 235, a circuit is closed from the positive current source 251 through the left-hand winding of ringing cut-off relay 250, sequence switch contact 262, the lower contact and armature of relay 240, conductor 257, the ring contacts of plug 224 and jack 225, line conductor 256, relays 255 in multiple, line conductor 254, the tip contacts of jack 225 and plug 224, the upper armature and front contact of relay 240, conductor 253 and sequence switch contact 263, to ground. The bell of station R responds to this current as previously described.

If the signaling of party M is desired, only contact 426 is closed and therefore relay 220 becomes deenergized when sequence

switch 205 reaches position 11, its circuit being open at contact 260. The sequence switch 205 stops in position 12, from which position it is moved out under the control of cam 233 in the same manner as was described in connection with the signaling of party W. The ringing circuit for party M is established through sequence switch contacts 264 and 258, the ringing relay 240 being energized when sequence switch 205 leaves position 11. 70

If party J or a direct line is desired, then contacts 426, 425 and 430 are closed. When sequence switch 205 reaches position 14, a circuit is established from grounded battery through contact 430, conductor 431, sequence switch contacts 265 and 222, and the right-hand front contact, armature and winding of relay 220 to ground. This relay holds its armature attracted in position 15 of sequence switch 205, and the sequence switch is moved into position 17. In position 16 of the sequence switch, relay 220 becomes deenergized and closes the circuit of relay 240, whereupon the ringing circuit is established through sequence switch contacts 266 and 263. 80 85 90

It will be seen from the above that the circuit of ringing relay 240 adapted to associate the selected ringing current source 95 with the line, is maintained open at the left-hand back contact of relay 220 until sequence switch 205 reaches positions 8, 11, 14 and 16, respectively, depending upon the setting of indicator 406. If, for example, the signaling of party R is desired, the ringing relay cannot become energized until after sequence switch 205 has left position 14, and therefore the ringing of stations W and M, while this sequence switch is moving 100 105 through its operating positions 10 and 13, positively prevented.

Although only one trunk 147, 148 extending between the district selector and plug 224 has been shown in Fig. 2 of the drawings, it will be obvious to those skilled in the art that in commercial telephone systems there are a plurality of such trunks, each trunk being provided with controlling apparatus (relays, sequence switches, etc.) 110 115 similar to those shown in Fig. 2.

What is claimed is:

1. In a telephone exchange system, a plurality of offices, a calling line terminating in one office and a called line terminating in a second office, a plurality of stations associated with said called line, trunk lines extending between said offices, variably operable connecting means for extending said calling line to one end and other variably operable connecting means for extending said called line to the other end of any one of said trunk lines, a plurality of different selective signaling means for said stations at said second office, and means in- 120 125 130

- cluding a switch common to said plurality of trunk lines and controllable from said first mentioned office for controlling the association of any one of said signaling means 5 with the called line irrespective of the variations in the operation of either of said connecting means.
2. In a telephone exchange system, a plurality of offices, a calling line terminating in one office and a called line terminating in a second office, a plurality of stations associated with said called line, a plurality of trunk lines extending between the offices, a variably operable selector switch for extending the calling line to one end and variably operable connecting means for extending the called line to the other end of any one of said trunk lines, a plurality of different selective signaling means for said stations at said second office, and controlling means including a switch at said second office common to said plurality of trunk lines and controllable from the first office for associating any one of said signaling means 20 with the called line irrespective of the variations in the operation of said selector or connecting means.
3. In a telephone exchange system, a plurality of offices, a calling line terminating in one office and a called line terminating in a second office, trunk lines extending between said offices, means for extending the calling line to one end and means for extending the called line to another end of any one of said trunks, a called number indicating device at the second office common to said trunks, controlling apparatus for said device at the first office, a plurality of different selective signaling means for said stations, and means dependent on the operation of said indicating device for associating a signaling means with the called line.
4. In a telephone exchange system, a calling and a called line, a plurality of stations associated with said called line, trunk lines, connecting means for extending said calling line to one end and other connecting means for extending said called line to the other end of any one of said trunk lines, a plurality of different selective signaling means for said stations, a variably operable switching device adapted to associate in each of its operating positions a different signaling means with the line, controlling apparatus for said switching device located at a distant point, means operable in accordance with the adjustment of said controlling apparatus for moving said switching device into a position next to the desired position, and separate means operative thereupon for moving said switching device into the desired operating position to associate a signaling means with the called line.
5. In a signaling system, a line, a plurality of stations associated therewith, a plurality of different selective signaling means for said stations, a variably operable switching device adapted to associate in each of its operating positions a different signaling means with the line, variably adjustable means for causing the movement of said switching device into a position next to the desired position, and separate means operative thereupon for moving said switching device into the desired position to associate a signaling means with the line.
6. In a signaling system, a line, a plurality of stations associated with said line, a plurality of different selective signaling means for said stations, a variably operable switching device for selecting a signaling means, means controllable from a distant point for moving said switching device to a position next to the desired operating position, a relay adapted to connect the signaling means to the line in all operating positions of said device, means associated with said switching device for causing it to move to the desired position and means for actuating said relay only when said device moves into said desired operating positions.
7. In combination, a telephone line having a plurality of talking conductors, two subscribers' stations on said line, signaling devices at said stations, respectively, each associated with a different conductor, a source of ringing current, a hunting switch for joining said source to one or the other of said conductors, and manually controlled contacts for governing the stopping of said switch.
8. The combination with a telephone connecting circuit, of a ringing circuit having a plurality of branches, a controlling circuit having a plurality of branches corresponding in number with the branches of said ringing circuit, switching mechanism for closing any branch of said controlling circuit, and an automatic switch adapted in its movement to establish corresponding branches of said ringing circuit and said controlling circuit one after the other, said controlling circuit being adapted to control the movement of said automatic switch to bring the same to rest in a position corresponding with the particular branch of the controlling circuit that is closed.
9. In a telephone system, the combination with a plurality of connecting circuits, of a multiple-branch ringing circuit associated with each of said connecting circuits, an electromagnetic switch controlling the closure of each of said branches, operator's switching mechanism common to said connecting circuits and adapted to be brought into association with any one of the same, said switching mechanism being adapted to control said branch-controlling electromagnetic switch, and signals associated with said operator's switching mechanism and

130

under the control of said electromagnetic switches, whereby the electromagnetic switch is indicated.

10. In a telephone system, the combination with a plurality of connecting circuits each having a plurality of ringing control switches adapted to be set to apply different sorts of ringing currents to the associated circuit, of a signal device adapted to be brought into operative relation with the ringing control switches of any of said connecting circuits to indicate which one of said ringing control switches is set.

11. In a telephone system, the combination with a plurality of connecting circuits, of a plurality of sources of ringing current, switching mechanism associated with each of said circuits and adapted to be set selectively to control the application to the associated circuit of ringing current from said various sources, operator's keys for controlling the selective setting of said switching mechanism, said keys being adapted to be brought temporarily into association with any of said connecting circuits, and indicating means associated with said keys for indicating the setting of the switching mechanism of the connecting circuit with which said keys are at the time in association.

12. In a telephone system, the combination with a connecting circuit, of a ringing circuit having a plurality of branches, a controlling circuit having corresponding branches, means for changing the electrical condition of any one of said controlling cir-

cuit branches, an automatic switch adapted in its movement successively to establish the branches of said ringing circuit and simultaneously bring itself under the control of the corresponding branches of the controlling circuit, and means responsive to the changed electrical condition of any controlling branch for stopping said switch.

13. In a telephone system, the combination with a connecting circuit, of a ringing current generator adapted to deliver impulses of ringing current and pick up impulses having a predetermined relation to each other, a ringing circuit normally open at two points, a switch for closing the ringing circuit at one point, and an electrically actuated switch operated by a pick-up impulse for closing the ringing circuit at the other point.

14. In a telephone system, the combination with a connecting circuit, of a normally open ringing circuit having a plurality of normally open branches, an automatic switch adapted in its movement successively to close said branches, means for closing said ringing circuit and stopping said switch at a waiting point immediately preceding a branch-closing position of the switch, and means for moving said switch from said waiting point to said branch-closing point.

In witness whereof, I hereunto subscribe my name this 21st day of September A. D., 1916.

ALBEN E. LUNDELL.
